Primary Examiner — Cynthia M Chin(74) *Attorney, Agent, or Firm* — Haverstock & Owens LLP(57) **CLAIM**

I claim the ornamental design for a pitch-propelled vehicle, as shown and described.

DESCRIPTION

FIG. 1 illustrates a top perspective view of a pitch propelled vehicle.

FIG. 2 illustrates a bottom perspective view of a pitch propelled vehicle.

FIG. 3 illustrates a side view of a pitch propelled vehicle.

FIG. 4 illustrates a top view of a pitch propelled vehicle; and,

FIG. 5 illustrates a bottom view of a pitch propelled vehicle. The broken lines in FIGS. 2 & 5 depict portions of the vehicle which form no part of the claimed design.
